AUTOMATICALLY VARIABLE RESISTANCE

Gifford I. Holmes, Minneapolis, and Robert S. Craig, Robbinsdale, Minn., assignors to Minneapolis-Honeywell Regulator Company, Minneapolis, Minn., a corporation of Delaware

Application July 15, 1938, Serial No. 219,396

14 Claims. (Cl. 201—55)

This invention is directed broadly to a variable resistance, and more specifically to a resistance which is sealed within an enclosure and varied by means of a device responding to changes in a condition, such as temperature, pressure, humidity, etc., and which is located outside of the enclosure.

One of the most difficult problems to contend with in the design of an automatically variable resistance is that of a jumpy action between the resistance element and the element which moves across it. It is found, for example, that where a metallic slider is moved by means of a condition responsive element, such as a bellows or bimetallic thermostat, across a coiled resistance wire that there is a tendency, on a uniform change in temperature or pressure, for the slider to remain stationary for a time and then jump over a few of the coils, then remain stationary for another period after which it will again jump over a few more of the resistance coils. The effect of this is to reduce the number of positions which the slider can assume in travelling from one end of the resistance to the other, as well as to reduce the sensitivity of the condition responsive element moving the slider.

It is therefore an object of the present invention to design a resistance which is to be varied in accordance with the variation in a condition value wherein the resistance to movement between the resistance and the control member in contact therewith is reduced to a minimum so as to reduce the tendency for a jumpy action between them and also to increase the sensitivity of the condition responsive element producing the relative movement.

A further object is to provide a variable resistance in which the resistance element is a coiled wire and the element movable with respect thereto is a globule of mercury, fixed with respect to its support.

Another object of the invention is to provide a sealed glass enclosure in which is flexibly mounted a resistance element and to provide further an external force for moving the resistance element with respect to a globule of mercury within said enclosure.

Another object is to provide a resistance as set forth in the preceding paragraph wherein the external force is applied to the resistance by means of a movable magnet.

Another object is to mount the magnet on a carriage which is pivoted on the same axis about which the resistance element swings, and to counter-balance the carriage and the resistance element by an adjustable weight.

Still another object is to seal the tube with a flexible seal through which the support for the resistance element extends so that it can be swung back and forth with respect to the tube.

A further object is to flexibly mount the resistance element within the tube, weight it so that it will always hang substantially vertically, and then rock the tube back and forth.

5 These and other objects will readily become apparent as the following specification is read in the light of the accompanying drawing in which:

Figure 1 is a front view, partly in elevation and 10 partly in section of one form of our invention;

Figure 2 is a section taken along the lines 2—2 of Figure 1 and looking in the direction of the arrows;

15 Figure 3 is a detail view of some of the parts looking in the direction of Figure 1, other parts being omitted for the sake of clarity;

Figure 4 is a front view, partly in elevation and partly in section of a second form of our invention; and

20 Figure 5 is a front view, partly in elevation and partly in section of a third form of our invention.

Referring first to the modification disclosed in Figures 1, 2, and 3 it will be seen that the base

25 11 supports a bracket, generally indicated at 12, by means of the screws 13. The bracket 12 comprises a first knife edge 14, a ring portion 15, and a second knife edge 16 all of which are integrally connected. A sealed glass tube 17 which

30 is of a constant depth from front to back but which is flared at the lower portion in respect to its width as shown in Figure 1 is suitably connected to and supported by the ring 15. At the bottom of the glass tube 17 is an indentation as

35 indicated at 18 in which is positioned a globule of mercury 19. Sealed into the upper end of the tube 17 is a flexible metal strip 21 to which is connected within the tube a supporting arm 22. The arm 22 at its lower end carries a bar magnet 23 and an insulating member 24 which supports in any suitable manner two resistance elements 25 and 26 which are in the form of tightly coiled wires.

40 It will be noted with reference to Figures 1 and 2 that a small portion of each of the resistance elements is in contact with the globule of mercury which electrically connects these portions of the resistances. Resistance element 26 is connected by conductor 28 and the conductors 29 and 30 are connected to opposite ends of the resistance element 25. As the resistances are moved back and forth across the globule of mercury 19 various portions of the resistances will be electrically connected together.

45 These resistances while not of the usual form are of the type which may be used in a control circuit such as is disclosed in the application of John E. Haines, Serial No. 38,946. It will be noted in connection with Figure 2 that the conductor 28 is electrically connected to the arm 22 which is in turn electrically connected to the

50 55 60

resilient strip 21 and the external conductor 33. The conductors 29 and 30 are sealed into the upper end of the tube 17 and are connected to the external conductors 34 and 35, respectively.

A supporting carriage 37 is in the form of an inverted U and is provided with two pockets such as is indicated at 38 each having a bearing portion 39 to accommodate the two knife edges 14 and 16. When the U-shaped element 37 is placed over the knife edges the two legs of the element are disposed on opposite sides of the tube 17. The lower extremity of each leg is provided with a cutaway portion 40 into which the two legs of the horse shoe magnet 41 are adapted to fit. The horse shoe magnet is connected to the carriage 37 by means of screws 42 and clamps 43. As seen in Figure 2 the bar magnet 23 is located directly between the two legs of the horse shoe magnet and is so arranged that the north and south poles of the horse shoe magnet are adjacent south and north poles, respectively, of the bar magnet. It might be pointed out here that if desired a soft iron core could be substituted for the bar magnet and satisfactory results obtained. The carriage 37 is preferably made of some non-magnetic material such as brass so as not to interfere with the passage of magnetic flux through member 23 from the poles of magnet 41.

On the upper end of the carriage 37 is a screw threaded stem 45 on which is adjustably threaded a counter weight 46 for the purpose of counter balancing the carriage 37, the horse shoe magnet 41, the arm 22, and the bar magnet 23. Stops 47 and 48 are provided at the lower part of the base 11 in the path of movement of the horse shoe magnet 41 to limit the extent of rotation of the carriage 37 about its knife edges 14 and 16. Stops 47 and 48 are outside the normal range of the magnet 41 and serve merely to protect the instrument from tipping too far in the event the counter weight 46 is placed in such position that it will tend to over balance the carriage 37, magnet 41, magnet 23, and support 22.

Adjustably mounted on pin 50 which is suitably secured to the base 11 is an arm 51 which carries at its end a coiled bimetallic thermostat 52 which on expansion and contraction is adapted to move an arm 53 to which it is suitably connected. The upper end of the arm 53 is adapted to carry one end of a coiled tension spring 54, the other end of which engages in the hole 35 in the upper end of the carriage 37, as viewed in Figure 2. The arm 53 and carriage 37 are provided with indentations 57 and 58, respectively, in which the opposite ends of a connecting rod 59 are adapted to bear. An arm 60 integrally connected to the arm 51 is provided for adjusting the position of the thermostat 52 on the base 11 to vary the temperature at which the thermostat will actuate the carriage 37.

The purpose of the tension spring 59 is to keep the carriage 37 and the arm 53 in engagement with the opposite ends of the connecting rod 59 so that on temperature variations the arm 53 will rock the carriage 37 back and forth about the knife edges 14 and 16, and carry with it the magnet 41. The flexibility of the strip 21 will permit the magnet 23 to follow the magnet 41 thereby moving the resistance elements. The tube 17 is held stationary by means of the ring 15 and the mercury 19 is also held stationary by the depression 18 so that as the temperature to which the thermostat 52 is subjected determines the position of the arm 53 it will also determine the position of the horse shoe magnet 41, the bar

magnet 23, and the relative positions of the resistance elements 25 and 26 and the globule of mercury 19.

This type of variable resistance has the advantage that the mercury has a fixed relation to its support so that the only sliding contact is between the mercury and the resistance elements. The resistance to movement therefore between the mercury and the resistance elements will be very slight so that the tendency for a jumpy action therebetween will be materially reduced. As a result the resistance to movement of the bimetallic element is also decreased so that its sensitivity is correspondingly increased.

The weight 46 may be adjusted on the screw threaded stem 45 until it is in a proper position to counterbalance the carriage 37 and magnet 41 as well as the arm 22, magnet 23, and resistance elements 25 and 26 as they are rotated by means of thermostat 52 as it responds to variations in temperature. The combined effect of the counterbalancing weight 46 and the mercury type of contactor is to so reduce the effort required to operate the control that a motion multiplying linkage may be used between the condition responsive element and the resistance element without materially affecting the sensitivity of the condition responsive element.

Referring now to the modification disclosed in Figure 4 it will be seen that the open end of a glass tube 70 is closed by means of a flexible metal bellows 71 which is sealed thereto. The tube and bellows are fixedly supported by means of a link 72 which is suitably connected to the base 73 by some means (not shown). The lower end of the tube 70 is provided with an indentation 74 in which is fixedly supported a globule of mercury 75. The bellows 71 is provided with a cross pin 76 on which is pivotally mounted an arm 77 which extends through an aperture in the bellows 71 and is sealed thereto as indicated at 78. The lower end of the arm 77 supports a resistance element 80 in the form of a coiled wire. One end of the coiled wire is electrically connected to the arm 77 to which is connected in turn an external conductor 81. Conductor 82 is connected to the other end of the resistance 80 and sealed through the glass tube as indicated at 83 and connected to external conductor 84. A conducting element 85 is sealed into the tube 70 at the indentation 74 and extends within the globule of mercury 75 and at its other end is connected to the external conductor 86.

A portion 87 of the base 73 extends forwardly in the form of a shelf on which is seated one end of bellows 88, the other end carrying a movable stem 89 which engages the lever 90 which in turn pivots about the knife edge 91 suitably connected to the base 73. The end of the lever 90 opposite the bellows 88 carries a projection 92 which centers one end of a compression spring 93, the other end of which seats about a centering cap 94 which is adjustably positioned by means of the screw 95 which may be screwed in and out of the shelf 87 by means of the knurled head 96. It will be seen that the compression spring 93 opposes rotation of the lever 90 about the knife edge 91 by means of the bellows 88 and therefore adjustment of the screw 95 which will vary the force exerted by the spring 93 will adjust the temperature or pressure at which the bellows 88 will rotate the lever 90.

The lever 90 is integrally connected to an upstanding arm 98 which has at its upper end a forwardly extending portion 99 having a slot 100

therein which engages the pin 181 on the outer end of the arm 17. Therefore as the tube 78 is fixed by means of the supporting ring 72 rotation of the lever 88 by the bellows 88 will cause a back and forth movement of the portion 98 of the arm 88 and a consequent rotation of the arm 17 about its pivot 78 and a movement of the resistance 88 back and forth across the globule of mercury 78 which will vary the relative amounts of resistance in the external circuits to which the conductors 81, 84, and 86 are connected.

This modification will have the advantages of the first modification also in that the globule of mercury remains fixed with respect to its support and has sliding engagement only with the resistance element 88.

Coming now to the modification disclosed in Figure 5 the sealed glass tube 118 is identical with the tube 17 of the first modification. This tube is supported by means of ring 111 integrally connected to the pin 112 shown in dotted lines which is pivotally mounted in the base 113 to provide for rotation of the tube 118. As in the other modifications the tube 118 is provided with an indentation 114 in which is fixedly mounted a globule of mercury 115. A conductor 116 is sealed through the tube at the indentation and has one end in electrical contact with the mercury 115 and the other end connected to an external conductor 118. A flexible strip 117 similar to that disclosed at 21 in the first modification is sealed into the upper end of the tube 118 and at its lower end is suitably connected to an arm 120 which at its lower end carries a weight 121 and an insulating member 122 which supports the resistance element 123 formed by a coiled resistance wire. The strip 117 is very flexible so that under the influence of the weight 121 the arm 120 will tend to remain in a vertical position regardless of the position of the tube 118.

One end of the resistance 123 is connected by means of conductor 125 to the arm 120 which through the element 117 is connected to external conductor 126. The other end of the resistance element 123 is connected to the conductor 127 which is sealed into the upper end of the glass tube 118 as indicated at 128 and is electrically connected to the external conductor 129.

As in the second modification a portion of the base 113 is bent forwardly to form a shelf 130 which supports a bellows 131 for operating a lever 132 about a knife edge 133 and which is opposed by the adjusting spring 134 in the same manner as described in the second modification. The force exerted by the spring 134 is adjusted by means of the adjusting screw 135. The lever 132 is integrally connected to an upstanding arm 137 which has a forwardly extending portion 138 at its upper end having a slot 139 therein. The ring 111 is connected to an arm 140 having a pin 150 thereon which rides in the slot 139 so that as the lever 132 is rocked back and forth by the bellows 131 the sides of slot 139 will engage the pin 150 and through the arm 140 rotate the tube 118 back and forth about its pivot 112 and as the resistance 123 remains substantially stationary under the influence of the weight 121 and the flexible support 117, the effect will be to move the mercury 115 back and forth along the resistance element 123 thereby varying the relative amount of resistance in the external circuits to which the conductors 126, 128, and 118 are connected.

To the ring 111 is integrally connected a screw threaded stem 155 on which is adjustably positioned a counter-weight 156 for the purpose of counter-balancing the tube 118 so that the bellows 131 may be made more sensitive.

It is therefore seen that each of the three modifications has the advantage that the mercury remains in fixed relation to its support and has a sliding engagement only with its resistance element and as such engagement offers a comparatively small resistance to relative movement that the chances of a jumpy or uneven action is materially reduced.

It is pointed out that the tubes in each case 15 may be evacuated and filled with hydrogen or other gas if desired. It is of course understood that the resistances and mercury are placed in a sealed tube for the purpose of preventing oxidation and corrosion of the resistance coils and the mercury.

Certain changes and modifications in this invention may occur to those who are skilled in the art and it is therefore understood that we are to be limited only by the scope of the appended claims and not by the specific embodiments disclosed.

We claim as our invention:

1. In a device of the character described comprising in combination, a sealed enclosure, a globule of mercury, means at the bottom of said enclosure for fixedly mounting said mercury with respect to said enclosure, a resistance element, said resistance element being hung from the upper part of said enclosure by means of a resilient hinge member and in contact with said mercury, magnetic means carried by said resilient member, magnetic means outside of said enclosure for attracting said magnetic means within said enclosure, and means for moving said magnetic means outside of said enclosure to cause movement of said resistance element across said mercury.

2. In combination, a sealed tube, a globule of mercury, a relatively small indentation in the bottom of said tube, said mercury being carried in said indentation and extending slightly above the floor of the tube, a resistance element, means supporting said resistance element from the upper part of said tube for swinging movement in contact with the surface of said mercury, magnetic means mounted within said tube on said supporting means, a magnetic element outside of said tube for attracting said magnetic means, and a condition responsive element for moving said magnetic element back and forth in response to variations in the value of the condition.

3. In combination, a sealed tube, a globule of mercury, means for mounting said mercury at the bottom of said tube and in fixed relation to said tube, a resistance element, means supporting said resistance element from the upper part of said tube for swinging movement in contact with said mercury, magnetic means mounted within said tube on said supporting means, a magnetic element comprising a horse shoe magnet located outside of and embracing the lower end of said tube, the two ends of said horse shoe being adjacent to and on opposite sides of said magnetic means, and means for swinging said horse shoe magnet about substantially the same axis as that about which said resistance element swings.

4. In a device of the character described comprising in combination, a glass tube having an open end, an indentation in the other end, a

globule of mercury in said indentation and extending slightly above it, a resistance element, a flexible bellows sealing the open end of said tube; a support for said resistance element extending through said bellows and sealed with respect thereto, said support holding said resistance element in contact with said mercury, and a condition responsive device outside of said tube and bellows engaging said support to cause said resistance element to move back and forth across said mercury on variations in the value of the condition to which said device responds.

5. In a device of the character described comprising in combination, a glass tube having an open end, an indentation in the other end, a globule of mercury in said indentation and extending slightly above it, a resistance element, a flexible bellows sealing the open end of said tube; a support for said resistance element pivoted inside of the enclosure formed by said tube and bellows and extending through said bellows and sealed with respect thereto, said support holding said resistance element in contact with said mercury, and a condition responsive device outside of said tube and bellows engaging said support to cause it to rotate about its pivot and move said resistance element across said mercury.

6. In combination, a pivotally mounted sealed tube, means at the bottom of the tube for supporting a globule of mercury in fixed relation to the tube, a globule of mercury supported therein, a resistance element, an arm carrying said resistance element, resilient means supporting said arm from the upper portion of said tube so that said resistance element is free to swing with respect to said tube back and forth across said mercury, a weight on said arm so that it will normally hang vertically, and means for rocking said tube back and forth to move said mercury across said resistance as said resistance remains substantially stationary.

7. In a device of the character described comprising in combination, a base, a carriage pivotally mounted on said base, a sealed glass tube supported on said carriage, an indentation in the bottom of said tube, a globule of mercury supported in said indentation, a resistance element, an arm carrying said resistance element, a flexible element suspending said arm from the top of said tube whereby said resistance element can swing back and forth with respect to said tube across said mercury, a weight on said arm so that it will normally hang vertically, a condition responsive device for rotating said carriage about its pivot to move said mercury across said resistance element while said resistance element remains substantially stationary, and an adjustable weight on said carriage above its pivot for properly counterbalancing said carriage and tube.

8. In a device of the character described, comprising in combination, a sealed container, a globule of mercury, means at the bottom of said tube for supporting said mercury in fixed relation to said tube, a resistance element, means supporting said resistance element within said tube and in contact with said mercury, weighted means holding said resistance element substantially stationary, and condition responsive means moving said mercury back and forth across said resistance element.

9. In a device of the character described, a hermetically sealed tube, a relatively small indentation in the floor of said tube, a globule of

mercury carried in said indentation, an elongated resistance element, a member carrying said resistance element, said member being sealed within said tube by laterally flexible means and movable with respect thereto, said resistance being held in a position so as to contact the surface of said globule of mercury, relative movement between said member and said tube causing a longitudinal movement of said resistance element with respect to said mercury, and means outside said tube for causing relative movement between said member and tube.

10. In a resistance device the combination of, an hermetically sealed casing having a relatively small indentation in the floor thereof, a globule of mercury in said indentation and extending slightly above the floor of said casing, a resistor slideable over the surface of said mercury, oscillatable mounting means for said resistor, laterally flexible means for sealing said mounting means to said casing, and condition responsive means for oscillating said mounting means to vary the effective resistance of said device.

11. In a resistance device the combination of, an hermetically sealed casing having a relatively small indentation in the floor thereof, a globule of mercury in said indentation and extending slightly above the floor of said casing, a resistor slideable over the surface of said mercury, oscillatable mounting means for said resistor, laterally flexible means for sealing said mounting means to said casing, and condition responsive means, including magnetic driving means, for oscillating said mounting means to vary the effective resistance of said device.

12. In a resistance device the combination of, an hermetically sealed casing having a relatively small indentation in the floor thereof, a globule of mercury in said indentation and extending slightly above the floor of said casing, a resistor slideable over the surface of said mercury, oscillatable mounting means for said resistor, laterally flexible means for sealing said mounting means to said casing, and condition responsive means for developing a force to produce relative movement between said mercury and said resistor to vary the effective resistance of said device.

13. In a resistance device the combination of, an hermetically sealed casing having a relatively small indentation in the floor thereof, a globule of mercury in said indentation and extending slightly above the floor of said casing, a resistor slideable over the surface of said mercury, oscillatable mounting means for said resistor, laterally flexible means for sealing said mounting means to said casing, condition responsive means movable in accordance with variations in a variable condition, and connecting means between said condition responsive means and said mounting means.

14. In a resistance device the combination of, an hermetically sealed casing having a relatively small indentation in the floor thereof, a globule of mercury in said indentation and extending slightly above the floor of said casing, a resistor slideable over the surface of said mercury, oscillatable mounting means for said resistor, laterally flexible means for sealing said mounting means to said casing, condition responsive means movable in accordance with variations in a variable condition, and connecting means including magnetic translating means between said condition responsive means and said mounting means.
